UNITED STATES PATENT OFFICE.

CHARLES H. HART, OF HARTFORD, CONNECTICUT.

HAND-OPERATED PLUGGER.

No. 904,126.

Specification of Letters Patent.

Patented Nov. 17, 1908.

Application filed May 10, 1905. Serial No. 259,662.

To all whom it may concern:

Be it known that I, CHARLES H. HARR, a citizen of the United States, and a resident of Hartford, in the county of Hartford and State of Connecticut, have invented and produced a new Hand-Operated Plugger, of which the following is a specification.

My invention relates to the class of hand tools in which a blow is obtained from a spring or the like which is placed under tension and then released in the operation of the tool to exert a force upon a hammer or like part.

The object of my invention is to provide a device of this class which, while being effectual for the purpose intended, may be constructed of small dimensions as compared with like tools of the prior art, and also to provide a device which shall have extreme ease and freedom of movement of the parts and consequently of operation.

One form of device in the use of which these objects may be attained is illustrated in the accompanying drawings, in which—

25 Figure 1 is a view in central, longitudinal section of a dental plugger embodying my invention. Fig. 2 is a detail view in cross-section through the plugger shown in Fig. 1 on dotted line *a—b*.

30 In the accompanying drawings, referring to Fig. 1, the numeral 1 denotes the casing or shell to and within which the other parts of the device are secured and located. A tip 2 is secured to the shell at one end, as by 35 means of interengaging screw threads, and a tip 3 is also secured, in a similar manner, to the opposite end of the shell. This shell has at one end a slot 4 preferably cut through each wall of the shell on diamet- 40 rically opposite sides; it will be understood, however, that a single slot cut through one wall only may be employed. A spindle 5 extends through and has lengthwise sliding movement within the shell, projecting out at 45 each end, and provided with means for attachment of the tools 6. This spindle is longitudinally grooved, as shown at 7, for the reception of a spline, which may be in the form of a screw 8 projecting through the tip 3 into the groove and preventing the spindle from rotary movement. This spindle contains a slot or recess 9, preferably extending 50 through the spindle on a diametrical line. Within this spindle a lever is located, this 55 lever being pivoted to the spindle as at 10.

This lever is provided with a shoulder forming a pawl 11', and the lever is also provided with a cam 12. A hammer 13 is fitted to slide within the casing or shell 1, this hammer being tubular to receive the spindle 5, 60 and the lever 11 as to a large part thereof is located within the hammer, the pawl 11' engaging a lip 14 on the inner surface of the hammer. A spring 15 forces the lever with the pawl 11' into engagement with the lip 65 14. The tip 3 has an inwardly projecting sleeve 16, the inner end of which is located in position to engage the cam 12 of the lever and thus swing it on its pivot as the spindle 5 is moved lengthwise. 70

A main spring 17 is located within the casing, one end of the spring resting against the hammer 13 and the other end of the spring resting against the wings 18 extending laterally from an adjusting nut 19. 75 These wings extend through the slots 4 and engage the inner threaded surface of an adjusting sleeve 20 mounted on the outer surface of the casing 1, the ends of the sleeve abutting against a shoulder on the casing 80 and a shoulder on the tip 3, which shoulders hold the sleeve against lengthwise movement.

A spring 21 rests with one end against a shoulder 22 on the spindle, the opposite end 85 resting against a collar 23. This collar is secured between the end of the tip 2 and a shoulder on the inner surface of the casing 1. The opening in the collar 23 is sufficiently large to permit the anvil 24 on the spindle 90 to move therethrough and project beyond the inner end thereof to receive the blow of the hammer.

In the operation of the device pressure being exerted as by a push or pull upon the 95 tool 6, the spindle is moved endwise within the casing. The pawl 11 engaging the lip 14 on the hammer 13, moves the latter with the spindle, placing a tension upon the spring 17. As the pawl is moved within the sleeve 100 16 the inner end engaging the cam 12 forces the pawl from engagement with the lip 4 and the hammer being thus freed is forced by the spring 17 downward striking against a shoulder on the spindle, this shoulder forming 105 an anvil 24 to receive the blow, which, of course, is imparted directly to the tool 6.

It will be seen from the above construction that the lever bearing the pawl and the disengaging cam being located within the 110

hammer a very compact device may be produced. The lever being pivoted at one end, and the cam being located at the opposite end, with the pawl between the two points 5 a construction is provided whereby but little throw of the lever is provided to disengage the parts, and this throw is procured owing to the extreme leverage, with but the exertion of a little power.

10. What I claim as my invention and desire to secure by Letters Patent is:—

1. A casing, a spindle slidably mounted therein and with an end projecting therefrom and having an anvil, a hammer mounted to reciprocate on said spindle and having an inwardly projecting lip, a trip lever pivoted at one end in a recess in the spindle, said lever having a cam and a pawl the latter located to engage said lip, means for forcing 15 the hammer against said anvil, means to engage the cam at the outer end of the lever to release it from engagement with the lip, and

means for returning the spindle to its normal position.

2. A casing, a spindle mounted to slide 25 within the casing and with an end projecting therefrom and having an anvil, a tubular hammer located within the shell and having a lip, a spring for forcing the hammer against said anvil, a sleeve secured to the shell and projecting inward from the end thereof within said spring and forming a support therefor, a lever pivoted within a recess in the spindle and within said hammer and with its opposite end projecting out of the end of the hammer and within said sleeve and having a pawl to engage a lip on the hammer and a cam at its end to engage said sleeve, and means for returning the spindle 30 to its normal position.

CHARLES H. HART.
